UNITED STATES PATENT OFFICE.

THOMAS J. BURY AND ONEY BURY, OF HOUSTON, TEXAS.

AERIAL PROJECTILE.

1,294,392.

Specification of Letters Patent.

Patented Feb. 18, 1919.

Application filed September 25, 1918. Serial No. 255,622.

To all whom it may concern:

Be it known that we, THOMAS J. BURY and ONEY BURY, citizens of the United States, residing at Houston, in the county of 5 Harris and State of Texas, have invented certain new and useful Improvements in Aerial Projectiles, of which the following is a specification, reference being had to the accompanying drawings.

10 This invention relates to an improved aerial projectile, and has for its primary object to provide a device which will be very destructive in its effects when discharged from an aeroplane upon enemy troops.

15 It is a more particular object of our invention to provide an aerial projectile or bomb having a plurality of radially disposed shrapnel containing barrels, explosive means to discharge the shrapnel from the barrels, 20 and impact actuated firing means for the explosive.

It is also another important object of the invention to provide means for destroying the projectile after the bullets or shrapnel 25 have been discharged to thereby prevent the enemy from obtaining knowledge of its construction.

The invention has for an additional object to provide an improved firing means which 30 will insure the ignition of the explosive when the projectile descends either upon land or water.

The invention has for a further general object to provide a device as above characterized which is relatively simple in its construction, effective and reliable for the purpose in view, and capable of manufacture at relatively small cost.

With the above and other objects in view, 40 the invention consists in the improved construction, combination and relative arrangement of the several parts as will be herein-after more fully described, subsequently claimed and illustrated in the accompanying 45 drawing in which similar reference characters designate corresponding parts throughout the several views, and wherein:—

Figure 1 is an elevation illustrating the preferred embodiment of our invention;

50 Fig. 2 is a longitudinal sectional view;

Fig. 3 is a section taken on the line 3—3

of Fig. 2; and

55 Fig. 4 is a fragmentary longitudinal section showing a timing fuse for delaying the ignition of the explosive whereby the projectile is destroyed.

Referring in detail to the drawing, 5 designates a shell or cylinder which is adapted to contain an explosive for the purpose of destroying the projectile. This shell, at one of its ends, is threaded into one end of a cylindrical chamber 6. A cap 7 is threaded upon the other end of the shell 5 and a similar cap 8 is threaded on the lower end of the chamber 6. 9 designates a stem centrally connected to the cap 6, to which the directing vane or blade 10 is secured.

At equi-distantly spaced points, nipples 11 are secured in the wall of the chamber 6, and tubes 12 extend inwardly from these 70 nipples to a central, longitudinally extending tube 13 arranged within the chamber 6 which contains the ignition explosive. In the outer ends of the nipples 11, radially extending barrels 14 are threaded. These barrels are 75 adapted to be tightly packed with bullets or shrapnel slugs and an expelling charge of explosive in the inner end of each barrel.

The cap 8 is centrally formed with a nipple 15 in which a bushing 16 is fitted to 80 receive an explosive cap 17. A tube 18 is diametrically enlarged at one of its ends and threaded upon the nipple 15. In this tube, a guide sleeve 19 is secured and in said sleeve the firing pin 20 is loosely engaged. 85

A plunger rod 21 is movable in the tube 18 and is formed with a head 22 at one end to engage the firing pin. The other end of said rod projects beyond the end of the tube 18, and a collar 23 is formed on said rod. 90 A disk 24 of soft rubber is retained upon the lower end of the rod 21 and against the collar 23 by the nut 25 which is threaded on said rod, said disk being also engaged with the lower end of the tube 18. 95

Preferably, we also provide a fuse 26 extending through the wall of the cap 8 and through the tube 13. The ignition of the explosive in said tube may thus be assured in case the impact actuated firing means 100 should fail of operation.

In the operation of the device, as above described, when the projectile is thrown from an aeroplane, it is directed in a substantially perpendicular position during its 105 descent by the vane or blade 10. When the lower end of the plunger rod 21 strikes the ground, the impact causes a compression of the rubber disk 24 which normally holds the plunger rod in such position that the point 110 of the firing pin 20 is spaced from the cap 17. In this compression of the rubber disk,

the rod 21 moves upwardly in the tube 18 and forces the point of the pin 20 into engagement with the explosive cap, whereby the powder in the tube 13 will be ignited. 5 The flame from the exploded powder passing through the vent tubes 12, enters the nipples 11 and ignites the expelling charges in the several barrels 14. Thus, the shrapnel slugs or bullets are discharged from said barrels 10 in a plurality of radial directions with great destructive effect upon enemy troops in the vicinity of the projectile. The cylinder 5 is filled with an explosive which is ignited immediately after the discharge of the shrapnel from the barrels 14 so that thereby the projectile is completely destroyed and the enemy cannot obtain knowledge of its construction.

Obviously this chamber 5 might also be 20 filled with projectiles such as shrapnel.

If it is desired to delay the destruction of the projectile for a sufficient length of time as to make certain of the complete discharge of all of the barrels 14 we may interpose between the shell 5 and cylinder 6, a cylinder 25 27 having a reduced threaded end 28 for engagement in the end of the chamber 6 and a nipple 29 projecting longitudinally from said reduced end of the cylinder. A slow 30 burning fuse 30 of any desired length extends through this nipple and upwardly into the cylinder 27. When the cylinder is connected to the chamber 6, the nipple 29 extends into the tube 13, as seen in Fig. 4, 35 the fuse 30 being disposed in the explosive in said tube. Thus, when the explosive in the tube 13 is ignited and flame passes through the vent tubes 12 to the barrels 14, the fuse 30 is also ignited, and slowly burns until it 40 reaches the explosive in the shell 5. There will thus be an appreciable lapse of time after the contents of the barrels have been discharged before the projectile is destroyed.

The distance above the ground at which 45 the bullets or shrapnel projectiles are discharged from the barrels 14 may be regulated as desired by providing guide tubes 18 for the plunger 21 of various lengths. The soft rubber disk 24 will also yield upon 50 impact with water so that the disk will be sufficiently compressed to fire the cap 17. Thus, the projectile will be effective when discharged upon either land or water.

From the foregoing description, taken in 55 connection with the accompanying drawings, it is believed that the construction, manner of operation, and several advantages of our invention will be clearly and fully understood. The device consists of relatively few parts, which are all of simple form and can be readily assembled. It will also be seen that the bomb or projectile is comparatively light in weight so that a large number of the projectiles can be carried 60 upon the machine. Of course, it will be

manifest that the number of barrels 14 may be increased as desired. The bullets or slugs discharged from these barrels will cover an extensive area and as they are ejected radially and horizontally from the body of 70 the projectile, great destruction of the enemy's forces will result. We have herein illustrated and described what we believe to be a very practical embodiment of our invention, but it will be understood that the 75 form and proportions of the several parts, and the manner of assembling the same are susceptible of considerable modification and we, accordingly, reserve the privilege of adopting all such legitimate changes as may 80 be fairly embodied within the spirit and scope of the invention as claimed.

We claim:—

1. An aerial bomb comprising a body, a plurality of shrapnel containing barrels 85 detachably engaged with the body and projecting radially therefrom, an explosive containing chamber disposed within the body and having flame conducting tubes extending from the container to the several barrels to ignite the charges therein, impact actuated firing means detachably engaged with the lower end of the body and adapted to ignite the charge within said chamber, and a fuse extending into said chamber and 90 adapted to be lighted in order to cause the ignition of said explosive if the impact actuated means does not operate.

2. An aerial projectile comprising a circular hollow body having a reducing cap at 100 its lower end and formed with a centrally disposed axle tube adapted to contain an explosive, means for detonating the explosive including a tube detachably engaged with the reducing cap and extending below the 105 same, a firing pin disposed in said tube, an actuating plunger for the pin and projecting beyond the tube, a plurality of radially disposed shrapnel containing barrels 110 detachably engaged with the body and having their inner ends connected by flame conducting tubes to the central tubular portion of the body, and a charge containing chamber detachably connected to the upper end of the body and with which said central tube 115 communicates.

3. An aerial projectile comprising a body, a plurality of shrapnel containing barrels connected to said body, a container for an ignition explosive arranged in the body, 120 flame conducting tubes connecting the container to the several barrels, means for firing the explosive including a firing pin, an actuating plunger for said pin normally disposed in spaced relation thereto, and a 125 disk secured upon one end of said plunger and compressible under impact to permit of the movement of the plunger, whereby the firing pin is actuated.

4. An aerial projectile comprising a body, 130

a plurality of shrapnel containing barrels connected to said body, a container for an ignition explosive arranged in the body, flame conducting tubes connecting said container to the several barrels, means for igniting the explosive in said container including a tube connected to the body, a firing pin in said tube, an operating plunger for said pin movable in the tube, and a rubber disk secured upon the end of the plunger and engaged against the end of the tube,

said disk being compressible under impact whereby the plunger is operatively engaged with the firing pin.

In testimony whereof we hereunto affix 15 our signatures in the presence of two witnesses.
